UNITED STATES PATENT OFFICE.

JAMES E. MCNAUGHTON, OF MANCHESTER, VERMONT.

CHARCOAL-KILN.

SPECIFICATION forming part of Letters Patent No. 360,238, dated March 29, 1887.

Application filed September 2, 1886. Serial No. 212,515. (No model.)

To all whom it may concern:

Be it known that I, JAMES E. MCNAUGHTON, a citizen of the United States, residing at Manchester, in the county of Bennington and State of Vermont, have invented certain new and useful Improvements in Charcoal-Kilns, of which the following is a specification, reference being had therein to the accompanying drawings.

10 My invention has relation to certain new and useful improvements in the construction of metallic kilns or ovens for burning charcoal.

The invention has for its object to provide a kiln of simple and practical construction 15 that may readily be taken apart for transportation from place to place when desired, and that will be especially adapted for convenience and rapidity of charging and emptying, as will be more fully hereinafter described.

20 The apparatus consists in certain novel features of construction, that will be set forth hereinafter, and particularly pointed out in the claim appended.

In the accompanying drawings, Figure 1 represents a perspective view of the improved 25 kiln or oven; Fig. 2, a transverse sectional view, and Fig. 3 a side view of one end.

In these drawings, A designates a series of uprights planted or secured in the ground on 30 each side of the kiln proper, and connected by a series of cross-bars, B, extending across the top of the kiln, as shown, for the purpose of supporting and bracing the kiln. Between the said uprights A are arranged the sides 35 C of the kiln, each of which consist, preferably, of two long sheets of thin boiler-iron united by rivets, as shown. The lower sections of the sides are provided with two or more rows of apertures of the proper size and 40 distance apart for the proper supply of air to the burning wood. These sides are secured to the uprights or posts A by means of angle-irons D, to be hereinafter again referred to. The slightly-arched roof E is also preferably 45 composed of two sheets of thin boiler-iron, flanged at their edges and properly riveted together down the center of the furnace, forming a flange extending from end to end, as shown. An opening, F, may be made in the 50 said roof, for the purpose of firing the kiln and

for the escape of the gas. The longitudinal edges of the roof are provided with downwardly-extending flanges G, which are adapted to set over the upper edges of the sides C and be partially supported thereby.

The portions of the angle-irons D that are riveted to the sides of the kiln have their upper and inner edges beveled, so as to form recesses for the reception of the flanges G of the roof for the purpose of materially aiding in 60 the support of the same. To further support the roof I use eyebolts H, which pass through the cross-beams B, and are attached to the central flange formed down the center of the roof by the union of the two sections thereof. 65 The ends I, of the kiln also consist of thin sheets of boiler-iron, and may be provided with air-supply openings similar to those in the sides of the apparatus.

On the ends of the side and roof sections, 70 and projecting beyond both ends of the kiln, are secured a series of pins or studs, J, which are adapted to fit in coincident openings in the end plates I to detachably secure the same in place, as will be obvious.

75 Suitable doors, L, may be in one or both of the end plates, as may be desired.

When it is desired to charge the kiln, one or both of the end plates may be removed by simply sliding them off the pins on the side and 80 roof sections, and when the apparatus has been filled the end plates may as easily be replaced, and the apparatus will be ready for operation.

The principal advantage of this invention is that all the parts are constructed of such 85 comparatively light material and in such a manner as to allow them to be readily detached for transportation from place to place whenever it becomes necessary, which fact is of great importance in this class of apparatus, as those acquainted with the art to which it appertains will observe. Another great advantage 90 is that by making the ends removable the kiln may be quickly and conveniently filled, and as readily emptied.

95 It is obvious that, in case I desire to enlarge the kiln, I may construct the roof and side sections of a number of sheets of iron, as the exigencies of the case may require, without in the least departing from the spirit of my invention.

Being aware that it is not new to construct portable charcoal-kilns of metallic plates bolted together, and to provide such kilns with air-supply openings at or near the ground, I
5 wish it understood that I do not claim such construction as my invention.

- I am aware that it is old in kilns to construct the same of sheet-metal plates riveted together and braced in a practical position.
10 Such kilns have been made in the form of parallelograms, domes, and in other forms. They have been sustained by independent frames and eye-suspending bolts. Such devices I disclaim.
15 I am not aware that a rectangular knock-down kiln constructed as described by me has ever been provided with removable ends applied, as described, by sustaining-pins, and provided with doors, whereby the said ends can
20 be readily detached and wagons backed into the kilns to conveniently remove the charcoal.

Having thus fully described my invention, what I claim, and desire to secure by Letters Patent, is as follows:

A charcoal-kiln consisting of vertical sides 25 and an arched roof formed of sheet-metal plates secured together, as described, rows of supporting-pins J, secured to the ends of said roof and side plates, the end plates of the kiln removably sustained by said pins, and upright 30 frames connected by angle-irons and eyebolts to the kiln-walls, all constructed and adapted to operate substantially as described.

In testimony whereof I affix my signature in presence of two witnesses.

JAMES E. McNAUGHTON.
